UNITED STATES PATENT OFFICE.

LYCUS D. PERRY, OF NEW ROCHELLE, NEW YORK, ASSIGNOR TO LUDWIG & COMPANY,
OF NEW YORK, N. Y., A CORPORATION OF NEW YORK.

GRAND-PIANO ACTION.

Application filed August 8, 1921. Serial No. 490,681.

To all whom it may concern:

Be it known that I, LYCUS D. PERRY, a citizen of the United States, residing at New Rochelle, in the county of Westchester and State of New York, have invented certain new and useful Improvements in Grand-Piano Actions, of which the following is a specification.

This invention relates to piano actions, 10 and more particularly to a piano action in which the hammer is actuated vertically, as in grand pianos.

In the various types of grand piano actions heretofore used, it has been necessary 15 to employ additional compensating means because of the gradually increasing weight of the hammers from the treble to the bass end of the scale. Various means, such as springs or weights, have been added to each 20 key or action unit to obtain the desired uniform resistance to the fingers in manipulating the keys. One method generally employed is the insertion of lead slugs in holes bored into the keys.

25 An object of the present invention is to produce a simplified piano action to actuate a vertically striking hammer which will meet the necessary requirements of touch. In accomplishing this object, in the present 30 invention, many of the regulating and actuating members used in the usual type of grand piano action are eliminated, and a single spring is substituted in each action unit which results in the production of an 35 efficient action and also compensates for the different weights of the hammers. By means of the present invention, a desired touch may be obtained throughout the key board and the cost of manufacture and regulation reduced.

In the accompanying drawings, I have shown one embodiment of the invention. In this showing:

Figure 1 is a side elevation of an action 45 unit, and,

Figure 2 is a detail view of the spring employed.

Referring to the drawings, the reference 50 numeral 1 designates the usual piano key pivotedly mounted upon a key frame 2. A capstan 3 is mounted on the key and is adapted to engage a wippen 4. The wippen is pivotedly connected to a flange 5 and normally rests upon the capstan. The flange 55 is secured to a stationary rail 6, carried by

or supported on a bracket 7. A jack 8 is pivotally connected to the wippen, as at 9. A hammer 10 is secured to a shank 11, the shank being pivotally connected to a flange 12, carried by a supporting rail 13. The 60 supporting rail is secured to an arm 14 of the bracket 7. A jack regulating device 15 is mounted on the supporting rail and is provided with a threaded element 16 having a head 17 adapted to engage the forward 65 end 18 of the jack. The compensating spring is connected to the wippen and the shank of the hammer. As shown, the spring comprises a body portion 19, the lower end of which is bent to form a coil 20 which 70 is adapted to be arranged in a recess in the top of the wippen and receives a pin 21 whereby the spring is pivotally supported on the wippen. The lower terminal is provided with an eye 22 for the reception 75 of a screw 23, to retain the spring in position and to regulate the strength of same. A dowel pin 24 is arranged in the shank of the hammer and a flexible element or cord 25 is connected thereto. The free end 80 of this cord is secured in a hook 26 formed on the end of the spring.

The hammer shank is provided with a knuckle 27 adapted to be engaged by the jack. When actuated, the hammer is adapted to strike a string 28 in the usual manner. A back check 29 is arranged on the rear of the key and is adapted to engage the hammer on the rebound. A stop 30 is carried by the supporting rail adapted to limit the 85 movement of the jack. A lever 31 is pivotally connected to the hammer rail 12 and carries a rest rail 31' at its free end. The rest rail 31' is provided with a pad or cushion 32 which acts as a bumper for the 90 hammer shank when the latter is suddenly released and when the back check 29 is not in position to catch the hammer, as when the key is struck and immediately released, as in staccato playing. The rail 31' is supported by a member 33 connected with a soft pedal (not shown) and adapted to be raised thereby for soft tones, as will be 95 obvious. A jack spring 34 is arranged between the jack and the wippen. Movement 100 of the jack in a reverse direction is controlled by a regulating screw 35 having a head 36 which may be provided with a cushion 37 and is adapted to engage an arm 38 carried by the wippen.

The operation of the device is as follows:

When the forward end of the key 1 is depressed, the rear end carrying the capstan is raised, lifting the wippen 4. The jack 8, assisted by the spring 19 raises the shank and hammer toward the string 28. As the forward end 18 of the jack comes in contact with the regulating button 17, the jack spring 34 is compressed and the upper end of the jack 13 is disengaged from the hammer shank knuckle 27. The felt cushion 30 prevents the jack from traveling too far past its upper position when the momentum of the jack overcomes the resistance of the spring 34. The 18 hammer travels to the string by momentum and after striking it rebounds traveling downward until it is stopped by contact with back check 29. In the checked position, the knuckle 27 is nearer to the jack pivot 9 than 20 when the jack is in striking position, hence the spring 19 is placed under additional tension. In the return of the key to the position of rest, the first part of the movement releases the hammer from the back check and 25 the spring 19 tends to raise the hammer, which tendency is augmented by the jack spring 34. At this moment, the upper end of the jack bears upon the curved surface of the knuckle 27 acting as an eccentric and the 30 jack is returned to striking position under the knuckle, before the key is fully returned to its normal position making it possible to repeat a stroke when the key is less than one-half returned to its normal position.

35 The elimination of excessive weight in the action unit greatly reduces friction, producing a smoother and more responsive touch. By the elimination of counter weights in the front of the keys, the hammers may be raised 40 by means of a lever 31 for soft effects and when so raised, the keys maintain their normal position. In the usual type of construction, when the hammers are raised for soft effects, the keys drop, and this is very undesirable.

45 The strain exerted by the spring 19 on the cord 25 which is in the general direction of the arrow is outward and away from the hammer shank pivot thereby exerting a force 50 in a substantially lateral direction on the wippen pivot. The spring 19 is regulated to compensate for nearly the entire weight of

the hammer and shank and as the strain on the wippen pivot is in a line forming an acute angle to the key, only a minor part of the 55 weight of the hammer and shank is transmitted to the capstan 3, and only a fraction of the difference in weight of the hammers is effective to the touch.

It is to be understood that the form of the 60 invention herewith shown and described is to be taken as a preferred example of the same, and that various changes in the shape, size, and arrangement of parts may be resorted to without departing from the spirit of the in- 65 vention or the scope of the subjoined claims.

I claim:

1. A grand piano action comprising a wippen pivotally mounted adjacent one end, a jack pivotally connected adjacent the opposite end of said wippen, a vertically striking hammer pivotally mounted above and contacting with the jack to be actuated thereby, and a spring connected adjacent its lower end to said wippen between the pivot thereof 75 and said jack, said spring being flexed to exert its greatest tension in alinement with its ends, the upper end of said spring being connected to said hammer substantially in vertical alinement with the lower end of said 80 spring.

2. A grand piano action comprising a wippen pivot adjacent one end, a jack carried by said wippen adjacent the opposite end thereof, a hammer pivotally mounted above 85 and contacting with the jack to be actuated thereby, a spring flexed to exert its greatest tension in alinement with its ends, said spring having its upper end connected with said hammer, a pin secured to said wippen 90 between the pivot thereof and said jack, said spring being provided adjacent its lower end with a coil surrounding said pin, said coil being disposed in substantially vertical alinement with the upper end of said spring, and a tension adjusting screw mounted in said wippen and adapted to engage the lower end of said spring.

In testimony whereof I affix my signature in presence of two witnesses.

LYCUS D. PERRY.
